Primary Examiner — Leanne Was-Englehart*(74) Attorney, Agent, or Firm* — Davidson Law Group, ALC; Payam Moradian(57) **CLAIM**

I claim the ornamental design for a door threshold rail, as shown and described.

DESCRIPTION

FIG. 1 is a perspective view of the door threshold rail, showing my new design;

FIG. 2 is a right side view thereof;

FIG. 3 is a left side view thereof;

FIG. 4 is a front side view thereof;

FIG. 5 is a back side view thereof;

FIG. 6 is a top view thereof; and,

FIG. 7 is a bottom view thereof.

The evenly spaced broken lines depict portions, of the door threshold rail that form no part of the claimed design.

The dot-dash broken lines depict a symbolic break. The portion between the break lines forms no part of the claimed design.
